UNITED STATES PATENT OFFICE.

JAMES B. HUDSON, OF TOLEDO, OHIO.

DESIGN FOR A HAND-STAMP.

SPECIFICATION forming part of Design No. 26,484, dated January 5, 1897.

Application filed September 5, 1896. Serial No. 605,034. Term of patent 7 years.

To all whom it may concern:

Be it known that I, JAMES B. HUDSON, of Toledo, county of Lucas, and State of Ohio, have invented a certain new and original Design for Stamps; and I do hereby declare that the following is a full, clear, and exact description of the invention, which will enable others skilled in the art to which it appertains to make and use the same, reference being had to the accompanying drawings, and to the figures of reference marked thereon, which form part of this specification.

This design relates to a stamp, in which--

Figure 1 is a perspective view of a stamp illustrating my design. Fig. 2 is a bottom plan view of the stamp, and Fig. 3 is a sectional detail view in further illustration thereof.

The leading feature of my design consists in the face of a stamp having raised ribs arranged longitudinally and laterally thereon in parallel relation forming squares the face of which are in a different plane from the lower edge of the ribs, the lateral ribs extending the full width of the face upon one side,

but only to the second longitudinal rib upon the opposite side, forming a longitudinal depression the full length of the face and the width of one of the squares.

1 designates a stamp-body, and 2 the lower facing of stamping material, having arranged upon its lower face longitudinal ribs 3 and integral lateral raised ribs 4, forming depressions 5, rectangular in contour. The lateral ribs 4 do not extend the full width of the stamp, but end at the second longitudinal rib 3 upon one side thereof, forming an oblong depression 6, extending the entire length of one of the longitudinal sides of the stamp.

What I claim is--

The design for a stamp substantially as shown and described.

In testimony that I claim the foregoing as my own I hereby affix my signature in presence of two witnesses.

JAMES B. HUDSON.
